UNITED STATES PATENT OFFICE.

SCOTT FRANK TAYLOR, OF HYDE PARK, MASSACHUSETTS.

LATHE.

1,088,850.

Specification of Letters Patent.

Patented Mar. 3, 1914.

Application filed December 27, 1910. Serial No. 599,285.

To all whom it may concern:

Be it known that I, SCOTT F. TAYLOR, residing at Hyde Park, in the county of Norfolk and State of Massachusetts, have invented an Improvement in Lathes, of which the following is a specification.

This invention relates to lathes, and has for its object to construct an improved cross-feed attachment for lathes arranged to guide the tool automatically in its movement toward and from the axis of the work. By my attachment bevel-gear blanks may be automatically faced off on their beveled sides at any angle desired, and then reversed and faced off on their straight sides, without disturbing the angular adjustment of the guide or templet which is employed, and without disturbing the setting of the tool, and this is one of its particular uses, but it may be used for other purposes. The templet, which is employed as the guide extends entirely across the lathe-bed, and its guiding-portion is formed according to the work to be done and is extended substantially throughout its length.

Figure 1 is a plan view of a cross-feed attachment for lathes embodying my invention, in connection with a sufficient portion of a lathe to illustrate its coöperative relation therewith. Fig. 2 is a vertical section taken on the dotted line 2—2, Fig. 1. Fig. 3 is an end view of the guide or templet for the tool.

a, a', represent the usual ways on the lathe-bed on which the lathe-carriage slides; *e* the cross-slide; *e'* the tool-post bearing the tool *e²*; *b* the head; and *c* the arbor bearing the work, which, as here shown for the purpose of illustration, is represented as a bevel-gear blank *d*. An arm *e³* is secured to the cross-slide, with or without a friction roll at its extremity, which extends outward and is designed and intended to continuously engage a guide or templet as will be hereinafter described.

f represents a spring-pressed pin which continuously engages the lathe-carriage, which acts to thrust said carriage in a direction toward the templet, to hold the arm *e³* in continuous engagement therewith.

h represents the guide or templet, which, is made as a plate, arranged transversely of or with respect to the ways and extended entirely across the lathe bed. Said plate has a hole intermediate its length which receives a bushing arranged on the upper projecting

end of a bolt *h'*, and is free to swing on said bolt as a center. Said bolt *h'* also serves as the securing means for a clamp which is provided to hold said plate *h*, in position to be engaged by the arm *e³* on the cross-slide or in a position remote therefrom. *h²* represents the upper clamping-member, and *h³* the lower clamping-member, and said members are arranged one above and the other below the lathe-bed, so as to engage said bed when the bolt *h'* which passes through them is tightened. Said clamp is movable along on the lathe-bed, and is held fixed in any position thereon by the bolt. The top face of the upper clamping-member *h²* is made flat, and the guiding-plate or templet has flat faced end-portions on its under side, adapted to engage the top of the upper clamping-member at both ends, to be thus supported by said member. Said plate *h* is provided with curved slots *h⁵* at both ends to receive locking-bolts *h⁶*, which extend through said slots and into holes in the upper clamping-member and by said bolts said plate is held securely, and being thus secured at both ends is not sensitive to vibrations.

One side or edge of the guide or templet *h* is arranged to serve as a guiding-portion to be engaged by the arm *e³* on the cross-slide, and, as here shown, said side or edge is made straight, for the reason that the bevel-gear blank is designed to be faced off in a straight line; and the guide or templet is held with said guiding-portion at any angle according to the angle of the face of the bevel-gear blank or other piece to be trued, preparatory to being cut. The point of the tool *e²* is guided in parallel with the side or edge thereof as it is moved transversely by the cross-slide in a direction toward and from the axis of the work. The guide or templet may be adjusted to any desired angle by loosening the bolts *h⁶*, and swinging it on the bolt as a center, the bolt, however, remaining tight so that the clamp is not loosened. Thus the guide or templet may be adjusted angularly independently of its holder. The clamp may also be moved along on the lathe-bed by loosening the bolt *h'*, without disturbing the adjustment of the guide or templet. When facing off bevel-gear blanks by the use of my attachment the bevel side of a blank may be faced off, then without disturbing the angle of the guide or templet said guide or templet may be moved to a remote position by sliding the

clamp along on the lathe-bed, and also without disturbing the setting of the tool, the blank may be removed and replaced in a reversed position and the straight side faced off, and then these operations may be repeated on other blanks with the result that all the blanks will be faced off alike.

I claim:—

In a lathe, the combination with a lathe-
10 carriage movable longitudinally of the lathe-
bed and having a cross-slide thereon bearing
a tool-post, a rigid arm projecting from said
slide over the lathe-bed, and having an en-
gaging-face at its end, a templet having an
15 abutting-face, means to secure said templet
to the lathe-bed with its abutting-face ex-
tended convergently with the normal path
of said engaging-face, as it is moved out-

wardly from the lathe-center, and in position
to permit the slide to carry its said arm for 20
a portion of its outward movement with its
face out of engagement with the abutting-
face of the templet and subsequently with
its face in engagement with said abutting-
face, to cause the carriage to be moved longi-
tudinally of the bed during further outward
movement of the slide, substantially as de-
scribed. 25

In testimony whereof, I have signed my
name to this specification, in the presence 30
of two subscribing witnesses.

SCOTT FRANK TAYLOR.
